UNITED STATES PATENT OFFICE.

WILLIAM H. MULLINS, OF SALEM, OHIO.

DESIGN FOR A ROOFING-TILE.

SPECIFICATION forming part of Design No. 24,085, dated March 5, 1895.

Application filed September 26, 1894. Serial No. 524,208. Term of patent 7 years.

To all whom it may concern:

Be it known that I, WILLIAM H. MULLINS, a citizen of the United States, residing at Salem, in the county of Columbiana and State of Ohio, have invented and produced a new and original Design for a Roofing-Tile, of which the following is a description, reference being had to the accompanying drawing, in which the figure is a perspective view illustrating my design.

The general purpose of this design is the ornamentation of roofs for buildings, having as a primary object the production of roofing-tiles which shall constitute a suitable covering for the better class of architectural structures; and which, owing to their Gothic form and peculiar pattern of adornment, are rendered specially attractive by the lights and shadows upon their surface. This being the nature of my invention its essential features reside in the tile shown and particularly described.

The illustration forming part of this specification represents a single detached shield-shaped tile or boss 1, which is set up in bold relief as shown, presenting in side elevation a horn-like appearance, and in a cross-section taken through its apex a conoidal outline. The tile or boss is embellished by a shell pattern which has its beginning at the apex or horn 2 of the tile and radiates to its border in all directions.

Having thus described my improved tile, what I claim, and desire to secure by Letters Patent, is—

The design for an ornamental roofing-tile, substantially as herein shown and described.

In testimony whereof I subscribe my signature in presence of two witnesses.

WM. H. MULLINS.
